UNITED STATES PATENT OFFICE.

GLEESON EDWARD ROBINSON, OF ESHER, ENGLAND, ASSIGNOR TO THE STRAND
ACCESSORIES COMPANY, LIMITED, OF LONDON, ENGLAND.

COMBINED TOBACCO-RECEPTACLE AND PIPE-FILLER.

1,063,066.

Specification of Letters Patent. Patented May 27, 1913.

Application filed December 6, 1910. Serial No. 585,945.

To all whom it may concern:

Be it known that I, GLEESON EDWARD ROBINSON, a subject of His Majesty the King of Great Britain, and a resident of Esher, in the county of Surrey, England, have invented a certain new and useful Combined Tobacco-Receiptacle and Pipe-Filler, of which the following is a specification.

The invention has reference to mechanism for filling pipes with tobacco, and has for its object to combine with such mechanism a receptacle adapted to contain the tobacco, and to adapt the receptacle and the said filling mechanism so that the tobacco can be most easily transferred from the receptacle to the pipe.

It has been customary hitherto for the tobacco to be contained in cylinders constructed of paper or other suitable material, each of which is adapted to contain a measured quantity of tobacco sufficient to fill a pipe, on the well-known principle of a cartridge. These cartridges are supplied in a case, from which they have heretofore been transferred one at a time as required to a metal cylinder fitted with a plunger, and so constructed that by operating the plunger the tobacco can be driven into the bowl of the pipe while the cartridge case is retained in the metal cylinder by means of projections at the lower end thereof which engage with the cartridge case and prevent it being ejected with the tobacco.

This invention comprises in one structure a tobacco pipe filler and a receptacle or magazine for containing a supply of tobacco cartridges, the device being so constructed that the magazine serves the double purpose of a receptacle for the cartridges and a handle for the filler.

Figure 1 is a plan view of one embodiment of the invention showing the case and the lid open, the plunger with its cylinder having been removed. Fig. 2 is a plan view of the plunger cylinder and plunger. Fig. 3 is a longitudinal vertical section of the plunger cylinder, the section being taken on the line $\alpha-\alpha$ of Fig. 2, and looking in the direction of the arrow $\alpha-\alpha$. Fig. 4 is a plan view of the cylinder end of the case showing a charge of tobacco driven a part of the way into a pipe by the plunger. Fig. 5 is a plan view showing the case closed and the lid secured by the plunger cylinder.

A is the case, receptacle or magazine for

the storage of tobacco cartridges used for successive fillings of a tobacco pipe. This magazine is preferably divided longitudinally by a partition b and is provided with a closing lid B which is preferably hinged to the magazine at one end thereof.

C is a filler barrel constituting a part of the filler. This barrel is preferably cylindrical in form open at both ends and adapted to receive the tobacco cartridge from which the tobacco is to be ejected or expelled into the pipe. It is provided with means for holding the casing of the cartridge while the tobacco is being expelled therefrom. The barrel C is preferably constructed in separable sections, a semi-cylindrical section c and a semi-cylindrical section c' . The section c is fixed to or integral with the outer end of the body of the magazine A and the section c' is fixed to or integral with the outer end of the lid B and extends about half way across said end. A tubular guide d forms a cylindrical extension of the barrel C and serves as a guide for the plunger cylinder E hereafter mentioned. The means for holding or retaining the cartridge case within the filler barrel are preferably in the form of roughened surfaces having a considerable area extending both longitudinally and circumferentially on the inner face of the barrel. This construction affords a secure grip of the cartridge case and not only holds the same within the barrel during the expulsion of the tobacco but prevents crinkling thereof.

The edge of the magazine is preferably provided with a guide or lip g over which the lid shuts, said guide lip serving to hold the lid when in closed position in its proper relative position to said case.

A plunger of any suitable form is adapted to pass through the filler barrel and through the cartridge case therein for pushing out or expelling the tobacco contained within said case into the pipe which covers the outer end of said filler barrel. In the form of embodiment herein shown the plunger D is secured within a plunger cylinder E, the shank e of the plunger being fixed to the closed end of said plunger cylinder. This plunger cylinder is open at its inner end and is adapted to fit and slide over the filler barrel C and it is provided with a longitudinal slot f which engages the meeting webs h and i which unite the sections of said filler

barrel with the body and lid respectively of the magazine when the plunger is inserted into the barrel. When the plunger cylinder E is pushed into the cylinder C it lies along 5 the outer end of the magazine and serves as a fastening device to secure the lid in closed position.

To fill a pipe with tobacco the plunger cylinder is withdrawn sufficiently to clear it 10 from the half c' but it may conveniently still remain, if desired, upon the cylindrical portion d. The lid B can then be opened and a cartridge removed and placed in the half cylinder c, after removing the empty 15 case, if such has been left therein, of the cartridge used on the last previous occasion. The lid is then closed, when the half c' comes into position over the half c and the cartridge is gripped between the roughened 20 surfaces. The pipe is then held with the open bowl opposite the left hand end of the cylinder C (as shown in Fig. 4) and the plunger cylinder pressed toward the pipe bowl, when the tobacco is forced into 25 the pipe bowl out of the cartridge case, the latter remaining in the cylinder. It will be seen that as soon as the pipe is filled the case is securely closed and is in a suitable condition 30 to be returned to the user's pocket without any further manipulation.

There is an advantage merely in carrying the filler attached to a case, but the invention also constitutes an improved filler by which a pipe is more readily charged than 35 hitherto; as with the ordinary form of filler there is difficulty in retaining the cylinder properly central with the pipe bowl while filling. This difficulty has hitherto been, to some extent, met by forming the end of the 40 cylinder with a crown of a taper form slightly to enter the pipe bowl and prevent the cylinder being pushed too far therein. In such construction the inside of the cylinder must be of less diameter than the top 45 of the bowl of the pipe. By combining the filler and case, a very convenient handle is provided by which the filler can be held firmly in position, and the case itself may form a stop against which to rest the bowl 50 of the pipe. Furthermore the case forms a handle by which to hold the filler while the cartridge is being transferred from the case to the filler.

What I claim is:—

55 1. A pocket tobacco case comprising a pipe filler adapted to receive a tobacco cartridge and provided with means for holding the cartridge case during the expulsion of the tobacco therefrom, and a cartridge 60 magazine fixed thereto and constituting a handle therefor.

2. A pocket tobacco case comprising a cartridge magazine, and a pipe filler fixed thereto at one end thereof, adapted to receive a tobacco cartridge and provided with

means for holding the cartridge case during the expulsion of the tobacco therefrom, said magazine constituting a handle for said filler.

3. A pocket tobacco case comprising a 70 filler barrel adapted to receive a tobacco cartridge and provided with means for holding the cartridge case during the expulsion of the tobacco therefrom, a plunger movable in said barrel for expelling the tobacco 75 therefrom, and a cartridge magazine fixed to said barrel and constituting a handle for the filler.

4. A pocket tobacco case comprising a 80 filler barrel composed of separable sections and adapted to receive a tobacco cartridge and provided with means for holding the cartridge case within said barrel during the expulsion of tobacco therefrom, a plunger movable in said barrel for expelling the tobacco 85 therefrom, and a cartridge magazine comprising a body and cover fixed respectively to different sections of said filler barrel and constituting a handle for the filler.

5. In combination a receptacle for containing tobacco cartridges, a pipe filler comprising a cylinder for the cartridge said pipe filler having a roughened surface to prevent the cartridge case following the tobacco 90 as the pipe is being filled, and a part of the filler adapted to be moved in to exert pressure upon the side of the cartridge to hold it against the roughened surface.

6. In combination a receptacle for containing tobacco cartridges, a pipe filler comprising a plunger and a cartridge containing cylinder the latter formed as an external part of said receptacle, means for retaining the cartridge case while the tobacco 100 is expelled therefrom and a cylinder adapted to slide over the cartridge cylinder, and carrying said plunger.

7. In combination a receptacle for containing tobacco cartridges, a pipe filler comprising a plunger and a cartridge containing cylinder the latter formed as an external part of said receptacle, means for retaining the cartridge case while the tobacco is expelled therefrom, and a cylinder adapted to 110 slide over the cartridge cylinder, and carrying said plunger which cylinder has also a slot to clear the connection between the internal cylinder and the receptacle.

8. In combination, a receptacle for containing tobacco cartridges, a lid for same and a pipe filler comprising a cylinder for the tobacco cartridge and a plunger, said filler forming a fastening to secure the lid 120 of the case.

9. A pocket tobacco case comprising a 125 filler barrel composed of separable sections and adapted to hold a tobacco cartridge during expulsion of tobacco therefrom, said barrel being provided with a roughened in-

terior surface extending longitudinally thereof and operative to hold the cartridge case and prevent crinkling thereof during such expulsion.

5 10. In combination a receptacle for containing tobacco cartridges and a pipe filler comprising a cylinder for the tobacco cartridge, the filler being formed as a part of said receptacle and having its cylinder formed
10 in parts.

11. In combination a receptacle for containing tobacco cartridges and a pipe filler comprising a cylinder for the tobacco cartridge, the filler being formed as a part of
15 said receptacle having its cylinder formed in parts and having a roughened surface to prevent the cartridge case following the tobacco as the pipe is being filled.

12. In combination, a receptacle for containing tobacco cartridges and a pipe filler comprising a cylinder for the tobacco cartridge and a plunger, said filler being formed as an external part of said receptacle and having its cylinder formed in parts, and a completely cylindrical portion carried by one of said parts.

13. In combination, a receptacle for containing tobacco cartridges formed in two parts, one being a body portion and the other a lid, and a pipe filler comprising a cylinder for the cartridge, said cylinder being formed in two parts one of said parts being carried by the body of the receptacle and the other by the lid.

35 14. Apparatus for filling pipes with tobacco cartridges comprising a pipe filler to receive a cartridge, a receptacle for containing further cartridges and means for retaining the cartridge case in the filler while the
40 tobacco is expelled therefrom, the said receptacle forming an integral part of the said filler, and the pipe filler comprising a cylinder formed in parts, a movable part adapted to slide over said divided cylinder to
45 unite the same, and a plunger carried by said movable part.

15. Apparatus for filling pipes with tobacco from tobacco cartridges comprising a pipe filler to receive a cartridge, a receptacle for containing further cartridges and means for retaining the cartridge case in the filler while the tobacco is expelled therefrom, the said receptacle forming an integral part of the said filler, and the pipe 50 55 filler comprising a cylinder formed in two parts, a slotted cylinder adapted to slide over said two part cylinder and to unite

same, and a plunger carried by said slotted cylinder.

16. In combination, a receptacle for containing tobacco cartridges formed in two parts, one being a body portion and the other a lid, a pipe filler comprising a cylinder formed in two parts one of said parts being carried by the body of the receptacle and the other by the lid, a slotted cylinder adapted to slide over said two part cylinder and to unite same, and a plunger carried by said slotted cylinder. 60 65

17. A pocket tobacco case comprising a 70
filler barrel composed of separable sections
and adapted to receive a tobacco cartridge
and provided with means for holding the
cartridge case within said barrel during the
expulsion of tobacco therefrom, a plunger
movable in said barrel for expelling the
tobacco therefrom, a tubular plunger guide
united with one section of said filler barrel,
and a cartridge magazine comprising a body
and cover fixed respectively to different sec- 80
tions of said filler barrel and constituting a
handle for the filler. 75

18. A pocket tobacco case comprising a cartridge magazine and a pipe filler having a filler barrel whereof a section is fixed to the body of said magazine and a section is fixed to the lid thereof. 85

19. A pocket tobacco case comprising a cartridge magazine, a filler barrel having a section fixed to the body of said magazine and a section fixed to the lid thereof, and an actuating device which expels the tobacco from a cartridge held within said barrel and simultaneously locks the lid in closed position on said case. . . . 95

20. A pocket tobacco case comprising a
filler barrel provided with means for hold-
ing the cartridge case within said barrel
during the expulsion of tobacco therefrom,
a cartridge magazine united by a web with
said barrel and adapted to serve as a handle
for the filler, a plunger tube adapted to slide
over said barrel and provided with a longi-
tudinal slot engaged by said web, and a
plunger carried by said tube and adapted
to expel the tobacco from the cartridge
within said barrel.

In testimony whereof I have hereunto set my hand in the presence of two subscribing witnesses.
